No. 895,145.

PATENTED AUG. 4, 1908.

P. S. BAUER.
CORN AND BUNION PLASTER.
APPLICATION FILED MAR. 1, 1907.

UNITED STATES PATENT OFFICE.

PERRY S. BAUER, OF CHICAGO, ILLINOIS, ASSIGNOR TO BAUER & BLACK, OF CHICAGO,
ILLINOIS, A CORPORATION OF ILLINOIS.

CORN AND BUNION PLASTER.

No. 895,145.

Specification of Letters Patent.

Patented Aug. 4, 1905.

Application filed March 1, 1907. Serial No. 360,042.

To all whom it may concern:

Be it known that I, PERRY S. BAUER, a citizen of the United States, residing at Chicago, in the county of Cook and State of Illinois, have invented new and useful Improvements in Corn and Bunion Plasters, of which the following is a specification.

This invention relates to corn and bunion plasters prepared for application by the user and its object is to provide for securing the plaster in place without producing a bulky and uncomfortable bandage beneath and at the sides of the toe.

Another object of this invention is to provide a double covering for the medicament whereby to confine the heat from the toe and cause the medicament to act quickly and with full effect.

In the accompanying drawings Figures 1 and 2 show the plaster applied to a corn. Fig. 3 shows the binding strip. Fig. 4 is a plan view of the plaster. Fig. 5 is a longitudinal sectional view of the plaster. Fig. 6 is a sectional view on the line 6—6 of Fig. 4. Fig. 7 is a detail view of a modification. Fig. 8 is a sectional view on the line 8—8 of Fig. 7. Fig. 9 is a perspective view of the plaster as it appears when applied.

Referring to the drawings 10 is the binding strip made of fabric provided on one side with a coating 11 of adhesive material. This strip has enlarged ends 12 and 13 and a narrow connecting part 14 (Fig. 4). A shield 15 having a central opening 16 and made of felt or other suitable material is affixed to one of the enlarged ends of the binding strip by the adhesive on the strip. This shield is also preferably provided with a coating 17 of adhesive material on its outer face so that it will stick to the toe as applied. A suitable medicament 18 is located on the binding strip within the opening in the shield.

In applying my improved plaster the shield is arranged on the toe with the medicament directly upon or above the corn, the binding strip is wrapped around the toe, and the coated side of the free end 13 is affixed to the outer uncoated side of the end 12 which carries the shield. Thus the shield and medicament are covered by both ends of

the strip, forming a double covering which confines the heat and causes the medicament to act quickly and thoroughly.

The end 12 of the strip is preferably of the same size as the shield to completely, or approximately cover it, and the end 13 is somewhat longer than the shield to adapt the plaster for toes of different sizes and so that the end 13 will cover the shield also. The connecting part 14 of the binding strip will lie between the adjacent toes and beneath the toe having the corn and it is made narrow so that it will not unnecessarily bind the toe and prevent the free movement thereof in walking, and also to avoid producing a bulky bandage which would be liable to wrinkle and rub and otherwise prove uncomfortable and injurious to the user. The binding strip may be made so that the connecting part thereof will not stick to the under side of the toe, and this can be accomplished by providing the strip with wings 14' (Fig. 3) which are coated with the adhesive and are folded over and upon the strip as shown in Figs. 4, 6; or a piece of fabric 20 with a non-adhesive outer face may be laid on the adhesive coated connecting part of the strip as shown in Figs. 7, 8.

The binding strip will securely hold the shield in its fixed position on the toe without danger of becoming disarranged in walking. The strip is large at its ends to cover the shield and thereby better secure it in place, and narrow where it contacts with the toe to reduce to a minimum the binding effect on the toe and the inconvenience to the user.

What I claim and desire to secure by Letters Patent is:

1. A corn or bunion plaster comprising a binding strip having adhesive material on one side thereof throughout its length, said strip having enlarged ends and a narrow part connecting the ends, a shield affixed to the adhesive side of said strip at one end thereof and provided with an opening, the other enlarged end of said strip being longer than the enlarged end which carries the shield, and a medicament located on the strip within the opening in the shield.

2. A corn or bunion plaster, comprising a

biuding strip having a coating of adhesive material on one side thereof, a shield affixed to the coated side of said strip at one end thereof and provided with an opening, and a medicament located on the strip within said opening, said strip having wings thereon between its ends folded upon the strip to pro-

vide a non-adhesive section thereon between the ends of the strip.

PERRY S. BAUER.
